UNITED STATES PATENT OFFICE

LEO J. GRUBMAN, OF BELLE HARBOR, NEW YORK, ASSIGNOR TO MARKON MANUFACTURING CO. INC., OF NEW YORK, N. Y., A CORPORATION OF NEW YORK

ARTIFICIAL EYE AND METHOD OF APPLYING EYELASHES THERETO

Application filed February 7, 1927. Serial No. 166,371.

This invention relates to artificial eyes and a method of applying eyelashes thereto, and has for its primary object to provide artificial eyes for use in dolls, display manikins and other figures wherein a simple and novel means is provided for fixedly securing the eyelash strands in definite projecting relation to the outer surface of the eye member together with a new method of applying 5 the individual eyelash strands whereby this 10 operation may be performed with expedition and accuracy.

More particularly, in a preferred embodiment of the invention, I provide an eyelash member of celluloid or other inherently resilient material in the form of a shell having a hemispherical wall with a slit cut therethrough in definitely predetermined relation to the geometrical center of said wall. The 15 method of applying the eyelash forming strands consists essentially in forcing the strands under pressure inwardly through said slit and thereby expanding the opposed wall sections of the shell so that upon the 20 withdrawal of the expanding means, the said 25 slit is closed by the contraction of the shell wall to its normal form and the lash forming strands thereby securely clamped and held between the edges of said slit.

It is another feature of my new method of applying the strands, to fold each individual strand at its center upon itself as it is inserted through the slit in the wall of the shell so that as the edges of the slit close upon the 30 folded portions of the strand, the externally projecting ends thereof are slightly separated and lie side by side to form two individual lash members. If desired, I may also apply upon the folded intermediate portions 35 of the lash strands at the inner side of the shell wall a small quantity of liquid adhesive for the purpose of greater security.

With the above and other objects in view, the invention consists in the improved artificial eye and the method of applying the eyelashes thereto as will be hereinafter more fully described, illustrated in the accompanying drawings and subsequently incorporated in the subjoined claims.

In the drawings, wherein I have disclosed

one simple and practical embodiment of the invention, and in which similar reference characters designate corresponding parts thereof throughout the several views,—

Figs. 1, 2, 3 and 4 illustrate the successive 55 steps in the method of applying the eyelash forming strands to the eye shell member, said member being illustrated in section;

Fig. 5 is a front end elevation of the eye member, and

Fig. 6 is a detail horizontal section on an enlarged scale taken substantially on the line 6—6 of Fig. 3 and showing one of the eyelash forming strands in its applied position relative to the wall of the eye shell.

The invention forming the subject matter of this application, is in its essentials disclosed in Patent No. 1,569,480, issued to the Grubman Engineering & Manufacturing Company, Inc., on January 12, 1926. The 70 claimed subject matter of said issued patent relates to an apparatus or machine for automatically applying the eyelash forming strands to an artificial eye member and by the new method as claimed herein.

For purposes of illustration, I have shown in the accompanying drawings an eye shell member generally designated at 5 which may be drawn from a sheet of celluloid, or other inherently resilient material to provide a 80 hemispherical end wall 6 upon which the eye pupil and the eyelid may be painted or otherwise delineated in the manner customary in this art. In the drawings, I have shown the wall thickness of this eye shell greatly 85 exaggerated in order to better illustrate the essential characteristics of my present invention.

The hemispherical end wall 6 of the eye shell has a slit indicated at 7 cut therethrough. This slit is appropriately located with respect to the eye pupil as seen in Fig. 5 and the angle of the cut with respect to the center of radius of the hemispherical wall section 6 is also definitely predetermined. 90 This slit is normally closed, or in other words the opposed edges thereof are maintained in contacting engagement with each other by the inherent resiliency of the celluloid or other material. Therefore, it will be under- 95 100

stood that practically no material is removed from the shell wall to provide an unobstructed opening therethrough and that this slit 7 is in effect nothing more than a fracture of the shell wall.

5 The eyelash forming strands indicated at 8 in the requisite predetermined number and of proper length are now arranged with the central part of each strand opposed to the slit 7 at the outer side of the shell, and said 10 central portions of the strands are then engaged by the comparatively blunt edge 10 of a suitable tool blade 9. While the shell is held in a stationary position, pressure is applied by the edge of the blade 9 against the 15 central portions of the strands 8 to force the strands inwardly through said slit, the edge of the blade 9 expanding the hemispherical wall 6 of the shell at the opposite 20 sides of the slit. Thus, the intermediate portion of each strand is formed into a loop indicated at 11 which projects inwardly from the inner surface of the shell wall. When the edge of the tool blade 9 is withdrawn the 25 hemispherical wall 6 of the shell immediately contracts or returns to its normal condition and the upper and lower edges of the slit 7 exert a tight clamping pressure upon the two parts of each strand 8 extending 30 through said slit. As shown in Fig. 6 of the drawings, this clamping pressure results in a slight separation of the outwardly projecting end portions of the strand so that 35 they lie side by side in closely adjacent relation to form the individual eyelash members 12. Thus, it will be understood that the 40 number of strands 8 to be assembled with the tool blade 9 and inserted through the slit 7 is only one-half of the total number of individual eyelash members 12 which may be 45 required in accordance with the size of the eye member and the length of the slit 7.

Since the edges of the slit 7 clamp upon and securely hold the portions of the lash 50 forming strands extending through said slit, it will be evident that the angular relation which these edges of the slit bear to the outer hemispherical surface of the shell wall determines the angle at which the lash members 12 will project from said surface. After 55 the lash strands have been applied in this manner, the projecting ends of the strands may be curled or curved as illustrated in Fig. 4 of the drawings.

55 For all reasonable uses to which the figure provided with my new artificial eyes would be subjected, the resilient clamping confinement of the eyelash strands between the edges of the slits 7 is sufficient to securely hold said strands against casual displacement or disengagement from said slit. However if desired, for purposes of greater security, after the eyelash strands have been arranged in the manner above explained, I 60 may apply a suitable liquid cement indi-

cated at 14 to the inner surface of the shell wall over the strand loops 11, thus securely interlocking said loops with each other and also adhesively connecting the same with the inner surface of the shell wall.

From the foregoing description considered in connection with the accompanying drawings, the improved artificial eye structure as well as the method of applying the eyelashes will be clearly and fully understood. It will be evident that by means of my new method, together with the structural provision in the wall of the eye shell for securely fixing the lashes in their applied position, the quantity production of such artificial eyes may be greatly expedited and with an appreciable reduction in cost. By means thereof, the use of adhesive or additional holding or clamping means for the inner ends of the eyelash strands may in many cases be wholly dispensed with without impairing the security of the connection to such an extent as to render the article commercially impractical. I have herein disclosed a preferred method of applying or attaching the eyelash forming strands to the artificial eye shell, but it will be understood that in so far as the structure of said shell is concerned and the means whereby the lashes are held in fixed connection therewith, it is not essential that each strand shall be folded centrally on itself to form the two individual eyelash members, since it is obvious that each eyelash member may be formed from a separate strand. Therefore, it is to be understood that while I have herein described a preferred and satisfactory embodiment of my present improvements, the same might also be incorporated in various other alternative structures, and I therefore, reserve the privilege of resorting to all such legitimate changes therein as may be fairly embodied within the spirit and scope of the invention as claimed.

I claim:

1. In an artificial eye, an eye shell of resilient material having a closed slit in its wall, and eyelashes having parts engaged through said slit and fixedly clamped between the opposed edges thereof by the inherent resiliency of the wall structure tending to close said slit.
2. In an artificial eye, an eye shell of resilient material having a normally closed slit in its wall presenting opposed edges in predetermined angular relation to the outer surface of the eye shell, and eyelashes extending through said slit and fixedly clamped between the edges thereof by the inherent resiliency of the wall structure tending to close the slit and maintaining the eyelashes in a definite angularly projecting relation to the outer surface of the shell wall.
3. In an artificial eye, an eye shell of resilient material having a closed slit in its

wall, eyelashes extending through said slit and having parts projecting internally and externally from the shell wall, the portions of the eyelashes engaged in said slit being fixedly held by the inherent resiliency of the shell wall tending to close said slit, and additional means for securing the internally projecting parts of the eyelashes in fixed relation to the shell wall.

10 4. In an artificial eye, an eye shell of resilient material having a closed slit in its wall, individual eyelash strands extending through said slit and fixedly held therein by the inherent resiliency of the shell wall tending to close said slit, portions of the individual strands projecting internally and externally from the shell wall, and additional means for connecting the internally projecting portions of the strands in fixed relation

20 to each other.

5. In an artificial eye, an eye shell of resilient material having a closed slit in its wall, individual eyelash strands extending through said slit and fixedly held therein by the inherent resiliency of the shell wall tending to close said slit, portions of the individual strands projecting internally and externally from the shell wall, and additional means interlocking the internally projected 25 parts of the strands with each other and securing the same in fixed relation to the shell wall.

6. In an artificial eye, an eye shell of resilient material having a closed slit in its wall, and a plurality of eyelash strands each folded upon itself and extending through said slit to provide end portions forming adjacent lash members projecting from the outer surface of the shell wall, and the parts 30 of the lash strands disposed through said slit being fixedly clamped by the inherent resiliency of the shell wall tending to close said slit.

7. In an artificial eye, an eye shell of resilient material having a closed slit in its wall, and a plurality of eyelash strands each folded upon itself and extending through said slit to provide end portions forming adjacent lash members projecting from the outer surface of the shell wall, the fold loops 50 of said strands projecting internally from the shell wall, means uniting said loops in fixed relation with each other, and the parts of the lash strands disposed through said slit being fixedly clamped by the inherent resiliency of the shell wall tending to close said slit.

8. As an improved article of manufacture, an artificial eye shell of resilient material 60 bearing the representation of a pupil on its surface and having a slit cut through its wall in appropriate relation to said pupil the edges of which are normally in contact and adapted to be separated under pressure 65 for the insertion of eyelash strands there-

through whereby said strands will be fixedly held, by forces inherent in the shell structure tending to close said slit, in a definite angularly projecting relation to the outer surface of the shell wall.

9. The method of applying eyelash strands to an artificial eye shell of resilient material which consists in first cutting a slit through the wall of the shell in predetermined angular relation to the outer surface of said wall, 70 then engaging parts of a plurality of eyelash strands with the edge of an expanding tool and forcing the same inwardly through said slit to thereby separate the edges of the slit and expand the shell wall and finally withdrawing said tool to permit the shell wall to contract and close said slit and thereby fixedly clamp the strands between the opposed edges of the slit with said strands projecting in definite angular relation to the surface of 80 the eye shell.

10. The method of applying eyelash strands to artificial eye shells of resilient material which consists in first cutting a slit through the wall of the eye shell in predetermined angular relation to the outer surface of the shell, then engaging the edge of an expanding tool with the central portions of a plurality of individual eyelash strands and forcing said strands under pressure through 90 said slit to thereby fold each strand upon itself and separate the edges of the slit, and then withdrawing the expanding tool to permit the shell wall to return to its normal condition and close said slit whereby the individual strands are subjected to a clamping confining pressure between the edges of the slit and the end portions of the strands are fixedly held in definitely spaced relation to each other and at a predetermined outwardly projecting angle from the surface of 100 the shell wall.

11. The method of applying eyelash strands to artificial eye shells of resilient material which consists in first cutting a slit through the wall of the eye shell in predetermined angular relation to the outer surface of the shell, then engaging the edge of an expanding tool with the central portions of a plurality of individual eyelash strands 110 and forcing said strands under pressure through said slit to thereby fold each strand upon itself and separate the edges of the slit with the folds of the strands projecting from the inner surface of the shell wall, and then withdrawing the expanding tool to permit the shell wall to return to its normal condition and close said slit whereby the individual strands are subjected to a clamping confining pressure between the edges of the slit and the end portions of the strands are fixedly held in definitely spaced relation to each other and at a predetermined outwardly projecting angle from the surface of the shell wall, 120

130 and finally fixedly uniting the inwardly pro-

jecting folds of the strands against movement relative to each other and with respect to the shell wall.

12. As an improved article of manufacture, an artificial eye shell having a slit in its wall to receive eyelash strands, the material of the shell being resilient to provide means for fixedly holding the parts of the lash strands positioned in said slit against relative movement in the plane of the slit.

13. As an improved article of manufacture, an artificial eye shell of resilient material having opposed relatively yieldable portions between which eyelash strands are adapted to be inserted upon the relative separation of said portions, and said portions exerting a clamping confining pressure upon the lash strands by the inherent resiliency of the shell wall to fixedly retain the lash strands in attached relation to the shell.

14. An artificial eye comprising an eye shell bearing the representation of a pupil on its surface and having a slit through its wall in appropriate relation to said pupil, eyelash strands having portions engaged in said slit, and said shell having a yielding portion constituting means fixedly holding the lash strands against an edge of said slit in the shell wall.

30 In testimony that I claim the foregoing as my invention, I have signed my name hereto.

LEO J. GRUBMAN.
